CLAIM

The ornamental design for a wound dressing, as shown and described.

DESCRIPTION

FIG. 1 is a top, front perspective view of the wound dressing of the present invention;

FIG. 2 is a top plan view of the wound dressing illustrated in FIG. 1;

FIG. 3 is a bottom plan view of the wound dressing illustrated in FIG. 1;

FIG. 4 is a left side elevation view of the wound dressing illustrated in FIG. 1;

FIG. 5 is a right side elevation view of the wound dressing illustrated in FIG. 1;

FIG. 6 is a front elevation view of the wound dressing illustrated in FIG. 1;

FIG. 7 is a rear elevation view of the wound dressing illustrated in FIG. 1;

FIG. 8 is a top perspective view of the wound dressing illustrated in FIG. 1 in a slightly stretched state; and,

FIG. 9 is a top plan view of the wound dressing illustrated in FIG. 1 in a slightly stretched state.
